LIQUID FUEL BURNER

John D. Peterson, Bolton, N. C.

Application November 15, 1946, Serial No. 710,141

4 Claims. (Cl. 158—80)

1

My invention has for its object to provide an improved oil burner and heater adapted to be used as a central heating plant in buildings which are more or less of open construction such as tobacco barns, and which is of the wickless type capable of burning low grade oil as the fuel.

A further object of my invention is to provide an oil heater having a burner to which the fuel oil is supplied at its center and distributed radially over a hot plate to effect the vaporization of its volatile constituents, the excess flow being trapped in one or more concentric annular depressions which increase the surface area of the burner and aid in the further vaporization of the fuel.

A still further object of my invention comprehends a burner for fuel oil comprising an annular hot plate having a central oil receiving chamber and a surrounding annular channel containing a dispersing ring which, like the plate is automatically heated and in combination therewith, aids in the volatilizing of the products of combustion.

Furthermore my invention has for its object to incorporate a burner having the aforescribed characteristics in combination with a surrounding drum which has the dual function of serving as a radiator and as the means of directing a circulation of air around the burner together with an interior down draft chamber mounted centrally above the burner to supply air for combustion, said casing and chamber combining to also provide the desired heated air for circulation throughout the building in which the apparatus is installed.

To these and other ends my invention has for its object to provide further improvements in construction, all as will be fully described in the accompanying specification, the novel features thereof being set forth in the appended claims.

In the drawings:

Figure 1 is a vertical sectional view of a heater and burner illustrating one embodiment of my invention.

Figure 2 is a horizontal section on the line 2x—2x of Fig. 1 showing a plan view of the burner.

Figure 3 is a front elevation of the entire unit.

Figure 4 is a side elevation, partly in section, of the base ring in which the burner is removably mounted.

Figure 5 is a vertical section of the burner plate alone taken on line 5x—5x of Fig. 2.

Figure 6 is a vertical section of one of the oil

2

dispersing rings which comprise part of the burner.

Figure 7 is a top plan view of the central down-draft chamber.

Figure 8 is a side elevation of the central dispersing cone forming part of the burner which is shown in section on Fig. 1.

Figure 9 is a detail illustration showing a modification in the cross-sectional shape of one of the oil recess channels and the ring therein.

Similar reference characters in the several figures indicate similar parts.

The heater and burner combination comprising my invention, as at present illustrated in Fig. 1, 15 comprises an outer cylindrical casing 1 surrounding a burner in the form of a flat plate 2 located slightly above its lower end on an annulus 3 within the casing. In practice I mount these parts on a concrete foundation comprising a platform or floor 4 surrounding a central well 5 from the lower end of which is a lateral air passage 6 of ample dimensions, the outer end of which extends beyond the foundations of the building to be heated and serves to furnish a continuous supply of fresh outside air beneath the heater.

The burner 2 is mounted centrally over said well and is removably mounted on the ring 3, the latter being supported on a number of adjustable leveling screws 3a projecting downwardly

from its lower side with their lower ends resting on the platform 4. By adjusting one or another of the screws the burner may be accurately maintained in a horizontal plane which is desirable for its most effective operation.

20 A free circulation of air beneath and around the casing 1 is obtained by supporting its lower edge a short distance above the platform and to this end I provide it with legs 7. A portion of this air also enters the casing through a series of apertures or perforations in the periphery of the ring 3.

25 The casing 1 is closed by a cover 8 and disposed centrally therein is a cylindrical chamber 9 open at its ends for supplying a down-draft for the burner. This chamber is adjustable vertically having at its lower end a cross bar 10 having a central perforation by means of which it is guided on an upwardly projecting pin 15 on the burner, its movement or setting relatively to the latter being effected by a series of spirally arranged perforations at its upper end with any one of which there may be engaged a pin 15a removably guided in an eye 16 on the top of the cover 8.

30 Flues 17 and 18 extend laterally from the sides of the casing 1 near its top and for the purpose

35

40

45

50

55

of effectively directing the products of combustion thereto I provide deflecting baffles 19 which curve outwardly and upwardly from a common central point above the burner.

At a point at one side of the casing it is provided with a door 20 which affords access to the burner and located above the casing is a flat deflector 21. This I support on arms 22 having at their lower ends cylindrical strap portions 23 which surround the flues and permit the deflector to be tilted into an angular position above the casing for directing the radiant heat waves therefrom to one side or the other. This is an important feature when the apparatus is used in conjunction with a more or less open building, such as a tobacco barn, as the circulation of air therein is affected by exterior air currents blowing against it and by using such a deflector it is possible to counteract such currents and obtain a more even distribution of the heat generated throughout the building.

The burner 2 which I employ is essentially one designed for the burning of low grade fuel oil and when first put into operation is heated by burning thereon a handful of oil soaked waste, or the like, to raise its temperature to a point where the fuel oil is vaporized, following which its continued operation is automatic.

At the center of the plate 2 is an inverted truncated conical cavity or recess 25, the annular sloping walls of which extend upwardly from a flat bottom to the surrounding horizontal surface of the plate. The fuel oil is introduced into this cavity from a nozzle 26 having lateral discharge openings. The nozzle is threaded into the bottom of the plate 2 and is supplied with oil, preferably by gravity, through a pipe 27 provided with a control valve 28 and connected to a supply tank exterior of the building and leading to the burner through the air duct 6 and well 5.

The volume of oil supplied to the cavity 25 is regulated somewhat by a cover piece 29 having a dome which fits over the nozzle and is provided with an annular bevelled edge paralleling that of the cavity 25 within which it is supported by a series of narrow ribs 30 of such thickness that only a narrow channel is provided for the escape and feeding of the oil onto the surrounding face of the plate 2.

It is essential in the operation of a burner in which the oil is fed directly to a heated surface for causing its vaporization that provision be made for its operation over varying periods of time under varying operating conditions without the personal attention of an operator and to this end and also to increase the efficiency of the burner I have provided additional features to be presently set forth. Surrounding the oil feed well or cavity 25 and spaced therefrom, as shown in Figs. 1 and 5, is an annular recess 35 which is preferably semi-circular in cross section. Fitted therein is a similarly shaped ring 36 of such dimensions that there exists between its lower curved face and the face of the recess a narrow channel. In the operation of the burner the ring becomes heated, along with the plate 2, hence any oil which has not been consumed and flows outwardly on the face of the plate is trapped in the recess 35 and the thin layer thereof is further subjected to the volatilizing effect of this heated channel and its ring. It is for this same reason that I also provide a second outer annular recess 37 which will receive excess oil that in burning may expand and fail to burn off in the first

mentioned recess. A second ring, similar to ring 36, may be mounted in recess 37 but in practice I have not found such to be necessary.

I have made provision to dispose of excess oil, as may occur at certain times, as for instance if the supply has been excessive before the burner has reached a generating temperature, by forming a depression or sump 38 in the bottom of recess 35 and placing in communication therewith an overflow pipe 39. The latter I also connect to the bottom of the outer recess 37 to provide for the escape of any liquid oil that may under any circumstances reach this point. The sump being circular has a considerable area and therefore to control its intake I provide on the lower side of the ring 36 a bead 40 fitting somewhat loosely therein. These parts being cast their fitting together is not of machined accuracy so it will be seen that when the burner is in operation oil that may flow into the recess 35 in excess of that which is volatilized will pass off to the outlet. The bead also serves to center the ring in its recess and if desired the ring may be further supported by laterally extending wings 41 overlying the face of plate 2.

While I have shown the circular recess 35 as semi-circular in cross section it will be understood that it may be shaped otherwise and in Fig. 9 I have indicated the recess 35a provided with inclined side walls and the ring 36a therein similarly formed.

I claim:

1. A liquid fuel burner comprising a plate adapted to be heated having a horizontal upper surface provided with a central oil well and a surrounding recess spaced therefrom semi-circular in cross section, a cover for said well, said cover and plate being spaced apart to provide a narrow outlet therebetween communicating the well with the face of the plate, a ring semicircular in cross section fitting into said recess, means for holding said ring in spaced relation with said semicircular recess to provide a narrow channel therebetween for the reception of oil flowing outwardly on the face of the plate, and an oil supply discharging into said well.

2. A liquid fuel burner comprising a plate adapted to be heated having a horizontal upper surface provided with a central oil well and a surrounding recess spaced therefrom semi-circular in cross section and containing a narrow sump in the bottom thereof, a cover for said well, said cover and plate being spaced apart to provide a narrow outlet therebetween communicating the well with the face of the plate, a ring semi-circular in cross section fitting in said recess and having a bead loosely fitting said sump for controlling the flow of oil into the sump, means for holding said ring in spaced relation with said semi-circular recess to provide a continuous narrow channel therebetween for the reception of oil flowing outwardly on the face of the plate, and a source of oil supply for the central oil well.

3. A liquid fuel burner comprising a plate adapted to be heated having a horizontal upper surface provided with a central oil well and a surrounding recess spaced therefrom semi-circular in cross section and containing a narrow sump in the bottom thereof, a cover for said well, said cover and plate being spaced apart to provide a narrow outlet therebetween communicating the well with the face of the plate, a ring semi-circular in cross section fitting in said recess and having a bead loosely fitting said sump

for controlling the flow of oil into the sump, means for holding said ring in spaced relation with said semi-circular recess to provide a continuous narrow channel therebetween for the reception of oil flowing outwardly on the face of the plate, a second recess surrounding said first recess serving to receive oil on the face of the plate escaping beyond said inner recess, and an oil supply pipe feeding into the central oil well.

4. A liquid fuel burner comprising a plate 10 adapted to be heated having a horizontal upper surface provided with a central oil well and a surrounding recess spaced therefrom semi-circular in cross section and containing a narrow sump in the bottom thereof, a cover for said well, said cover and plate being spaced apart to provide a narrow outlet therebetween communicating the well with the face of the plate, a ring 15 semi-circular in cross section fitting in said recess and having a bead loosely fitting said sump for controlling the flow of oil into the sump, means for holding said ring in spaced relation with said semi-circular recess to provide a continuous narrow channel therebetween for the reception of oil flowing outwardly on the face 20 of the plate, a second recess surrounding said first

recess serving to receive oil on the face of the plate escaping beyond said inner recess, overflow means associated with each of said recesses for removal of excess liquid oil therein, and an oil supply nozzle discharging into the central well.
